UNITED STATES PATENT OFFICE.

ALBERT D. SMITH, OF BELVIDERE, ILLINOIS, ASSIGNOR TO NATIONAL SEWING MACHINE COMPANY, OF BELVIDERE, ILLINOIS, A CORPORATION OF ILLINOIS.

SEWING-MACHINE FEEDING MECHANISM.

1,107,718.

Specification of Letters Patent. Patented Aug. 18, 1914.

Application filed December 7, 1909. Serial No. 531,848.

To all whom it may concern:

Be it known that I, ALBERT D. SMITH, a citizen of the United States, residing at Belvidere, in the county of Boone and State of Illinois, have invented certain new and useful Improvements in Sewing-Machine Feeding Mechanism, of which the following is a specification.

This invention relates in general to improvements in sewing machines and more particularly to the feed bar or plate for feeding the work under the presser foot and the primary object of the invention is to provide an improved device of this character so constructed as to present a minimum gripping surface to the work when thin material is being fed, to permit the material to be readily turned and twisted without stretching or pulling the material, and an extended surface to grip the work when coarser or heavier material is being used and which will also permit the presser foot to rest flat upon the goods when the feed bar is lowered.

A further object is to provide an improved device of this character which will be simple, durable and cheap in construction and effective and efficient in operation.

To the attainment of these ends and the accomplishment of other new and useful objects, as will appear, the invention consists in the features of novelty, in the construction, combination and arrangement of the several parts hereinafter more fully described and claimed and shown in the accompanying drawing, illustrating an embodiment of the invention, and in which—

Figure 1 is an end elevation of the operating mechanism for the feed bar showing a portion of the machine stand or base in section. Fig. 2 is a detail view taken on line 2—2 of Fig. 1. Fig. 3 is an enlarged detail sectional view taken on line 3—3 of Fig. 2 showing a portion of the presser foot and the manner in which the presser foot holds coarse material against the feed bar or plate. Fig. 4 is a detail perspective view of the feed bar or plate. Fig. 5 is a view similar to Fig. 3 showing the manner in which thin material or goods is gripped by the feed bar.

Referring more particularly to the drawing, and in the present exemplification of the invention, the numeral 10 designates the top of the stand or support for the ma-

chine, 11 the presser foot and 12 the needle, all of which may be of the ordinary and well known construction.

The feed bar designated generally by the reference numeral 13 is preferably constructed to form spaced parallel arms 14 which are provided on their upper face with teeth or serrations 15. Arranged between the arms 14 and spaced intermediate these arms is another arm 16 which is also provided on its upper face with teeth or serrations 17. This arm 16 is preferably somewhat shorter than the arms 14, so that the needle aperture 18 in the plate 19 may be located between the arms 14 and adjacent the free end of the arm 16. The plate 19 forms a closure for an aperture in the base plate and through which aperture access may be had to the shuttle mechanism. The plate is also provided with a slot 20 through which the teeth 17 on the arms 16 project and is also provided with slots 21 which are of a length somewhat greater than of slot 20 through which the teeth or serrations 15 on the arms 14 project. The teeth or serrations 17 on the arms 16 are slightly higher or deeper than the teeth or serrations on the arms 14 so that they will project above the plane of the tops of the teeth or serrations 15. All of these teeth or serrations are preferably inclined toward the rear in the ordinary and well known manner so that when the goods is placed below the presser foot and the latter lowered, the feed bar 13 will grip the goods and feed the latter under the presser foot when the feed bar is operated.

Any suitable means may be provided for operating the feed bar and in the present exemplification of this invention, there is provided a cam 22 which is secured to the main shaft 23 for rotation therewith. The feed bar 13 is supported upon a member 24 which is supported for sliding and pivotal movement upon a support 25. Connected with the support 25 is an arm 26 which projects over and rests upon the cam 22 so that when the shaft 23 is rotated in the ordinary and usual manner, the cam 22 will impart an up and down movement to the feed bar 13. The forward and backward movements of the feed bar is preferably accomplished by means of a link 27 which is pivotally connected at one end as at 28 to the member 24 and its free end is preferably

deflected as at 29, which end is adapted to be engaged by a member 30, which in turn is engaged by the cam 32, so that when the shaft is rotated the cam 32 will rock the member 30 and move the feed bar 13 in one direction against the tension of an elastic member or spring 33. This spring 33 serves as a means for returning the feed bar. However the specific construction of the operating mechanism for the feed bar forms no part of the present invention. With this improved construction, it will be seen that when the thin material as indicated at 34 in Fig. 5 is placed beneath the presser foot 11, and the presser foot lowered, the teeth or serrations 17 on the central arm or member 16 of the feed bar will engage the material and the presser foot will hold the material against the teeth on this arm and will 20 also support the presser foot so that the material will not come into contact with the teeth or serrations 15 on the side arms or members 14 of the feed bar. This construction will permit the feed bar to feed the 25 goods under the presser foot and will at the same time permit the thin material to be twisted or turned so as to be properly guided by the operator without the danger of the goods becoming drawn or puckered 30 by the teeth or serrations 15 on the arms 14. In other words the feed bar will present a minimum gripping surface to the thin material. When coarser material 35 is being operated upon, the presser foot 11 will force 35 the material owing to its thickness into engagement, not only with the teeth or serrations 17 on the arm 16 but also into engagement with the teeth or serrations 15 on the arms 14 so that all of the teeth or serrations 40 will grip the material thereby presenting a maximum gripping surface to the coarse material and when the coarse material is being operated upon, it may be readily guided or twisted by the operator without 45 danger of the teeth or serrations drawing or puckering the goods. It will also be apparent that no matter, whether thin or coarse material is being operated upon the feed bar during its cycle of operation will 50 be lowered so that the teeth or serrations on all of the arms will assume positions below the plate 19 and when in this position the lower face of the presser foot 11 being flat will rest flat upon the goods and hold the 55 goods in position so that the feed bar will

engage the goods and advance it, when the feed bar is again raised.

In order that the invention might be fully understood the details of the foregoing embodiment thereof have been thus specifically described, but

What is claimed as new is:

1. In a device of the character described, the combination of a feed bar having a roughened surface for engaging the material to feed the latter, a portion of the roughened surface projecting beyond the plane of the remaining portion of the surface, and a single presser foot coöperating with the feed bar, said presser-foot having a flat face extending entirely across the width of and coöperating with the said roughened surface of the presser-foot, said flat face being adapted to rest upon the material.

2. In a device of the character described, the combination of a feed bar provided with spaced arms rigidly secured thereto, each of said arms being provided on its upper face with gripping teeth, the extremities of the gripping teeth on one of the arms lying in a plane higher than the plane of the extremities of the gripping teeth on another of the arms, and a presser foot having a flat face, said presser foot coöperating with the teeth on the said arms and adapted to force the material into engagement with the highest teeth only, when thin material is being operated upon and to force the material into engagement with all of the teeth when coarse material is being operated upon.

3. The combination of a work feed bar provided with a roughened surface for engaging only a face of the material and a presser foot coöperating with the feed bar and having a surface adapted to engage and rest upon a face of the material, the portion of said work feed bar surface intermediate its edges being raised slightly above the remaining portion of the surface, and the entire portion of the said surface of the presser-foot being disposed in the same plane.

In testimony whereof I have signed my name to this specification, in the presence of two subscribing witnesses, on this 3rd day of December A. D. 1909.

ALBERT D. SMITH.
